UNITED STATES PATENT OFFICE.

HARRY G. KAUFMAN, OF NEW YORK, N. Y.

DESIGN FOR A RING.

Application filed June 25, 1924. Serial No. 9,973. Term of patent 7 years.

To all whom it may concern:

Be it known that I, HARRY G. KAUFMAN, my new design. Figure 1 is a side view of a ring, showing a citizen of the United States, and a resident of the city of New York, borough of Manhattan, in the county and State of New York, have invented a new, original, and ornamental Design for Ring, of which the following is a specification, reference being had to the accompanying drawing, forming part thereof.

Be it known that I, HARRY G. KAUFMAN, my new design. Figure 2 is an edge view of the ring shown in Figure 1. Figure 3 is a plan view of the ring shown in Figure 1.

I claim:—

The ornamental design for a ring, as shown.

HARRY G. KAUFMAN.
